CAP STAY

Samuel Springer, Chicago, Ill., assignor to Associated Military Stores, Chicago, Ill., a corporation of Illinois

Application April 26, 1944, Serial No. 532,791

2 Claims. (Cl. 2—199)

1

This invention relates in general to a cap stay, particularly for use with a military cap having a removable or interchangeable cover.

An important object of the invention is to provide a removable stay as a part of the cap frame structure to extend upwardly at the front of the cap for distending the cover, if desired, or removable if a soft cover is preferred.

A further object of the invention is to provide a removable stay for an interchangeable cap structure in which the front ornament is secured for also maintaining the stay in proper position.

A further object of the invention is to provide a stay structure of sufficient rigidity to support the front of the cap in raised position, and also sufficiently flexible to provide a curved roll or top effect for engaging the cap cover.

Other objects of the invention will appear in the specification and will be apparent from the accompanying drawing in which,

Fig. 1 is a front view of a cap with the front portion broken away to show the stay structure in accordance with the invention;

Fig. 2 is a side elevation of the cap of Fig. 1 with the front portion of the cap broken away to illustrate the stay structure of this invention in cross section;

Fig. 3 is a perspective of a stay with parts broken away and separated to show its interior construction; and

Fig. 4 is a detailed section through the vizor strap fastening.

Military caps having head band and vizor frames with removable interchangeable covers have heretofore been provided so that several different styles of covers may be used with the same frame. Some military organizations wear their caps with the front cover raised or extended upwardly, while in other services, it is desirable to have the front of the cap arranged in a soft roll.

The present invention provides a construction which may utilize the same cap cover and frame for either of the above services, and also provides additional supporting means for the cap ornament usually worn at the front of the cap.

Referring now more particularly to the drawings, a cap structure is shown having a flexible outer band 10 usually made of stiff buckram covered with cloth with a vizor 11 at the front and a soft cloth finishing roll 12 along the lower edge of the band. Extending inwardly from the supporting band 10 is a cushioned sweat band 13 of any desired construction and size.

At the ends of the vizor in the cap frame are

15 grommets 14' to receive fastening buttons 14 inserted therethrough at the ends of a vizor strap 15 for holding the strap in place.

The cap cover 16 may be of any desired material and may be of different colors for ordinary or dress service, so that the same frame may be used for these different covers. The front of each cover is somewhat higher than the rear, and extending downwardly from the top structure is a 20 flexible band 17 of a size to fit closely over the stiff upstanding band 10 of the cap frame. At the sides of the band 17 are grommets 18 registering in position with the grommets 14' of the frame so that the fastening buttons 14 are inserted through the grommets 18 in securing the 25 cap cover in place.

At the front of the cap frame and secured to the front of the stiffened band 10 is a strap 20 preferably secured at the ends only by rivets or 20 grommets 21, leaving the interior space between the ends entirely unobstructed and forming with the adjacent edge of the band 10, a receiving 25 slot for the lower end of a stay 22.

This stay has a stiffening layer 23 such as 25 buckram supporting a felt pad 24 between it and an upright fabric support 25 having metal strips 26 in its side edges. At the top is a crosspiece 27 comprising a metal strip 28 enclosed in a fabric cover 29, the entire structure being enclosed in 30 outside cover sheets 30, and a top margin cover 31 which secures the crosspiece 27 in place in a slightly rounded condition, turned over at the top and rounded downwardly from the center to form a shaped upper edge at the top of the stay for 35 engaging the inside of the cap cover and always supporting it in a smooth curve.

At the central portion of the stay is a grommet 32 which is inserted through the covers, through the buckram sheet 23 and through the upright 40 support 25 and also the felt packing 24 for holding all of the parts together. The stay is somewhat wedge-shaped, smaller at the bottom and rounded at the top, adapted to be inserted in the space between the strap 20 and the band 10, the 45 grommet 32 registering with a grommet 33 in the front portion of the cap so that the threaded stem 34 of a cap ornament 35 at the front of the cap may be inserted therethrough and engaged from the inside of the cap by a threaded lock nut 36.

With this construction, the stay may be inserted from the inside of the cap without removing the cover of the cap from the frame. The stay is adjusted until its grommet 32 registers with the grommet 33 of the cap, and the cap ornament is inserted therethrough and locked

in place. To remove the stay, this operation is reversed, and in order to change the cap cover without removing the stay, it is necessary to remove the front ornament and replace it on the new cap cover. To remove or replace a cap cover, it is also necessary to remove the cap screws 14 which are locked on at the inside of the cap in the same way as the front ornament.

Although the stay structure is described in some detail, it is apparent that various other changes may be made without departing from the spirit and scope of the invention.

I claim:

1. A flexible stay for distending the front of a hat cover with respect to a supporting frame therefor, the said stay comprising a wedge-shaped assembly of flexible material including an outer cover having a top edge binding, a layer of stiffening material within and conforming to the shape of the cover, an upright fabric support within the cover and having metal strips in its opposed side edges, a pad within the cover disposed between the layer of stiffening material and the upright fabric support, and a grommet extending through the cover, layer of stiffening material, pad, and upright fabric support for holding them all together.

2. A stay for supporting the front of a cap cover relative to a cap frame, comprising a

wedge-shaped assembly of flexible material including an outer cover, a layer of stiffening material within the cover, an upright fabric support having metal strips in its side edges within the cover, a pad of cushioning material within the cover and disposed between the layer of stiffening material and the fabric support, a top cross piece extending throughout the width of the cover and above the layer of stiffening material, upright fabric support, and pad of cushioning material, the cross piece including a fabric strip having a metal strip therein, and a top edge binding securing the cross piece in place in a slightly rounded condition in the provision of a curved contact edge for engaging the inside of the cap cover.

SAMUEL SPRINGER.
